CLAIM

The ornamental design for a thermal insulating board for a laptop computer, as shown and described.

DESCRIPTION

FIG. 1 is a top perspective view of the upper surface of a thermal insulating board for a laptop computer according to the present invention;

FIG. 2 is another top perspective view thereof wherein a laptop computer is illustrated in broken lines and is not claimed;

FIG. 3 is a bottom perspective view thereof;

FIG. 4 is a bottom view;

FIG. 5 is a top view; and

FIG. 6 is a front view thereof;

FIG. 7 is a rear view thereof;

FIG. 8 is a side view thereof; and,

FIG. 9 is the opposite side view thereof.
